ASH TRAY

John Squires, Hagerstown, Md.

Application September 14, 1931
Serial No. 562,717

7 Claims. (Cl. 131—51)

The invention relates to ash trays and the principal objects thereof are to provide an article of this character having cigarette or cigar supporting means which will prevent the falling of ashes or burning parts of a cigarette or cigar over the side of the tray, and hence prevent damage to table tops, carpets or the like around the tray; to provide an improved cigarette or cigar supporting means in the form of a clip which can readily be associated with a container such as a dish or the like, whether or not the container has side walls flaring outwardly or inwardly; to provide an ash tray having cigarette or cigar supporting means of novel character which can be manufactured in an inexpensive manner from sheet metal; to provide improved cigarette or cigar supporting means in the form of a bridge constructed of sheet metal which is adapted to be supported by the edge of a dish or other suitable container whether or not the walls of the container flare outwardly; and to provide novel means for supporting cigars or cigarettes above and within the boundaries of a container.

25 For a better understanding of the invention reference may be had to the accompanying drawings forming a part of the specification wherein:

Fig. 1 is a plan view of an ash tray constructed according to one form of the invention;

30 Fig. 2 is a front elevational view of the construction shown by Fig. 1, also showing certain parts in cross section for the purpose of further illustrating the arrangement;

Fig. 3 is an end view of the cigar or cigarette supporting means shown by Fig. 2, as seen when separated from the ash receiving container;

35 Fig. 4 is a plan view of an ash tray having cigar or cigarette supporting means constructed according to another form of the invention;

40 Fig. 5 is an end view of the cigar or cigarette supporting means shown by Fig. 4 as seen when separated from the ash container;

Fig. 6 is a plan view of an ash tray illustrating still another form of the invention;

45 Fig. 7 is a cross sectional view on a larger scale, taken substantially along line 7—7 of Fig. 6;

Fig. 8 is a front elevational view of the construction shown by Fig. 6;

50 Fig. 9 is a cross sectional view taken substantially along line 9—9 of Fig. 8;

Fig. 10 illustrates the manner in which the cigar or cigarette supporting means are fastened to a dish or container having side walls curved inwardly toward the center of the container; and

Fig. 11 illustrates the manner in which the cigar or cigarette supporting means are fastened to a dish having side walls flared outwardly and away from the center of the container.

Referring to Figs. 1 and 2, a container 10 is illustrated, which has an outwardly flared wall 11 terminating in an outwardly directed edge 12. The container may be an ordinary dish such as commonly used in households, or it may be manufactured and sold particularly for ash tray purposes, and in either event the container may be manufactured from glass, metal, earthenware or any other material suitable for the purpose.

As shown by the above figures, as well as by Fig. 3, a cigarette or cigar supporting member 13 is provided, which is constructed from thin and springy sheet metal. The supporting member comprises spaced side strips 14 and 15 extending in substantially parallel relation, and interconnecting cross strips indicated at 16. In the particular construction illustrated, four of the cross strips 16 are provided and as best shown by Figs. 2 and 3, each of the strips is provided intermediate its ends and between the strips 14 and 15 with an upwardly pressed, arcuate portion 17, which not only reinforces the assembly but normally will prevent depositing cigarettes on the strips longitudinally thereof. The entire construction may be stamped from sheet metal or the like, or the cross strips may be secured to the strips 14 and 15 in any suitable manner as by soldering or by welding. Between each pair of cross strips 16, the strips 14 and 15 are formed to

provide arcuate recesses or pockets 19, the pockets or recesses in one of the strips being aligned transversely with respect to the pockets or recesses in the other strip. The metal defining the pockets or recesses is adapted to support and maintain cigarettes, cigars or the like in position

above the container 10. It will be noted that between each pair of cross strips 16, and the strips 14 and 15, an open space 20 is obtained and this space has a particular and desirable purpose. In

supporting a cigarette, for example, it is disposed transversely of both strips 14 and 15 preferably, and in one of the pockets in said strips and when the cigarette burns, the burning end finally coincides with or is disposed over the opening 20.

When and if this is permitted to occur, the cigarette ordinarily will become overbalanced and fall through the space 20, into the container 10. In

any event, the ashes as well as the cigarette will fall into the container 10, either through the space 20 or at an outer side of the strips, if the

110

cigarette is allowed to burn sufficiently without changing its position.

The strips 14 and 15 at each end, are provided with arms 21 and 22 respectively, preferably slightly twisted intermediate their ends, and each of the arms terminates as best shown by Fig. 3 in a widened, reversely bent portion 23 adapted to have substantial engagement with the bead 12 on the container and retain the supporting means 5 on the latter. Each arm also is provided at its extreme end with a second portion 24 reversely bent with respect to the portion 23, which adapts the supporting member for cooperation with a container such as that shown by Fig. 10. It will be noted that the arms 21 and 22 at each end of the strips 14 and 15, diverge and hence will engage portions of the container that are spaced a considerable distance. This arrangement adds to the stability of the supporting means and renders the assembly less apt to become disarranged. It should be understood that the arms 21 and 22 are resilient and are sprung over the edges of the container and hence resiliently engage the latter.

25 Referring now to Figs. 4 and 5, the cigarette supporting member comprises a single, relatively wide strip 27 of sheet metal, which terminates at opposite ends in arms 28 and 29 arranged in substantially the same relation as the arms 21 and 22 in the construction shown by Fig. 1. These arms also terminate in widened, reversely bent portions such as shown in Fig. 3 for adapting the supporting means to different types of containers. Intermediate its ends, the strip 27 is 30 provided with cigarette retaining elements 30, arcuate in cross section, each of which is soldered or welded to the strip 27. In this construction as well as that shown in Fig. 1, the cigarettes or the ashes therefrom, will always fall into the 35 container and hence the danger of ashes, and burning cigarettes falling upon carpets or table tops around the container is avoided.

In both of the constructions so far illustrated and described, the metal strips extending across 40 the container are bowed upwardly, as shown by Fig. 2 for example, and this arrangement is desirable because cigarettes or cigars can be more conveniently disposed on and removed with respect to the supporting means therefor. Moreover, bowing the strips upwardly in this manner facilitates slipping the arms over the edges of the container as the entire resiliency of the supporting device can be brought into play, making it easier to secure it to the container. Also, bowing 45 the strips upwardly enhances the attractive appearance of the ash tray.

In the construction shown by Figs. 6, 7, 8 and 9, the cigarette supporting member comprises relatively narrow metal strips 33 and 34 having intermediate straight and parallel portions for supporting a plurality of elements 35 adapted to receive and retain a cigarette or cigar. These elements as best shown by Fig. 9, have opposite end portions 36 and 37 diverging downwardly, 50 which are respectively connected to the strips 33 and 34 preferably by soldering or welding. Each of the elements 35 is arcuate in cross section to adapt it for receiving cigarettes or cigars. The strips 33 and 34 at opposite ends diverge as indicated at 38 and 39 and terminate as shown by Fig. 7, in oppositely arranged reversely bent portions 40 and 41 adapted respectively to engage containers having different types of side walls as 55 previously described. The manner in which these reversely bent portions cooperate with different

types of containers is clearly shown by Figs. 10 and 11. It will be noted also in Fig. 6, that the strips 33 and 34 in the region of the reversely bent portions 40 and 41 also are widened, to obtain greater engaging surface contact with the container.

At one end, the diverging portions 38 and 39 of the strips 33 and 34 are connected by a depending U-shaped band 43, the upper ends of the legs of the band being flanged over and soldered or welded to the strips. This band is shaped to accommodate a box of matches of the pasteboard, clip type, well known in the art. The diverging portions of the strips at their other ends are connected by a second, depending band of generally U-shape as indicated at 44 which is similarly secured to the strips by welding or soldering. This band is of such shape as to accommodate the ordinary small wooden box of matches.

The cigarette and cigar supporting member shown by Fig. 6 is bowed upwardly similarly to the constructions previously described and is secured to the container in substantially the same manner. It will be noted however that the construction shown by Fig. 6 has bent portions for 100 engaging the containers that are reversely arranged with respect to the construction shown by Figs. 1 and 4 or in other words the first reversely bent portion in the construction shown by Figs. 1 and 2 is peculiarly adapted for cooperation with 105 the container shown by Fig. 11, and the second reversely bent portion is adapted to cooperate with the container shown by Fig. 10. The construction shown by Figs. 1 and 4 is so arranged that the first reversely bent portion is adapted 110 to cooperate with the container shown by Fig. 10, and the second reversely bent portion is adapted to cooperate with the container shown by Fig. 10.

From the above description taken in conjunction with the drawings, it is apparent that novel 115 forms of cigarette and cigar supporting means have been provided which are peculiarly adapted for cooperation with different types of containers and that they may readily be applied to or removed from containers. It is also apparent that 120 any of the constructions will prevent dropping of ashes or burning cigarettes or cigars around the container and upon carpets or table tops, and hence prevent damage to such articles. Moreover, it is apparent that any of the constructions can be 125 manufactured inexpensively from highly polished sheet metal or metal that has been plated with chromium, for enhancing the appearance of the ash tray.

It is also apparent that any of the constructions 130 may be utilized with a dish of suitable construction ordinarily used in households and hence the cigarette and cigar supporting means may be manufactured as a separate article and sold with the intention of its subsequent application to a 135 dish. Articles of the character described will meet with a wide public acceptance because of their neat appearance, ease with which they may be applied to different kinds of containers and their general adaptability for the purposes specified. Furthermore, ash trays such as described 140 will meet with wide public acceptance because they will prevent damage to carpets and tables and the like, that frequently has resulted from using ash trays of well known types.

Although certain forms of the invention have been described and illustrated in detail, it will be apparent to those skilled in the art that various modifications may be made without departing from the scope of the appended claims.

I claim:

1. In an ash tray, a supporting member for cigarettes or the like, comprising spaced strips of resilient sheet material, spaced strips connecting the first strips, said first strips being formed with aligned depressions between the cross strips for retaining cigarettes or the like, and clip means at the end of the first strips adapted to support the member on the walls of a container. 5 80
2. In an ash tray, an elongated member for supporting cigarettes or the like on a container, said member having diverging end portions, means on the latter for fastening the member to a container, and a match box retaining element 10 secured to diverging portions at one end of the member and extending therebetween, said element being of U-shape, and being suspended between the diverging portions. 85
3. An ash tray comprising spaced strips of resilient sheet material, terminating at their ends in diverging portions having clips for releasably fastening the tray to a container side wall, and match box receivers disposed between the diverging end portions at each end of the tray and being suspended by such diverging portions, to points adjacent the clip, one match box receiver 15 being adapted to receive the ordinary small wooden box of matches and the other receiver, the ordinary paper match clip. 90
4. An ash tray comprising spaced strips of resilient material terminating at their ends in diverging portions having clips for releasably fastening the tray to a container side wall, and strips of like material extending transversely 20 of and connecting the first strips at longitudinally spaced points, the longitudinally directed strips 95
- between the cross strips having aligned depressions for receiving cigarettes or the like, the cross strips between depressions being deflected upwardly to provide a means for preventing a cigarette or the like from being maintained on such cross strip. 100
5. An ash tray comprising a member terminating at its ends in clip portions for releasably fastening it to a container side wall, and cigarette holding means fastened to the upper surface of the member, each of said cigarette holding means having end portions inclined downwardly away from its center whereby ashes or the cigarette are more directly pointed into the tray and in the event of falling of either, there will be less likelihood of the cigarette or ashes being deposited outside of the tray. 105
6. An ash tray comprising longitudinally directed strips interconnected by cross strips, said longitudinally directed strips diverging at their ends and terminating in strip portions for releasably fastening them on a container side wall, the diverging end portions of the strips being twisted so as to favorably dispose the clip portions for receiving portions of the side wall of the container. 110
7. An ash tray comprising spaced strips of resilient sheet material, terminating at their ends in diverging portions having ends terminating in double, reversely bent portions adapting the assembled strips to be fastened on containers having inwardly or outwardly flared walls at spaced points at each end of the strips, and means connecting the strips at spaced points. 115
